WALTER T. DAVIS, OF WHEELING, WEST VIRGINIA, ASSIGNOR TO WHEELING STAMPING COMPANY, OF WHEELING, WEST VIRGINIA, A CORPORATION OF WEST VIRGINIA.

THREAD CUTTER FOR TUBE-WORKING MACHINES.

Application filed April 20, 1923. Serial No. 633,443.

The present invention relates broadly to the manufacture of collapsible tubes, and more particularly to thread-cutters for tube-working machines.

5 It has heretofore been proposed to form the threads in the necks of collapsible tubes by a rolling and pressing operation, without or substantially without the removal of any of the material of the tube. This 10 thread-forming operation has usually been carried out by supporting the tube to be threaded on a rotating mandrel and causing the roll or rolls to engage the rotating neck of the tube, said roll or rolls having threads 15 of the desired pitch in the cylindrical surface or surfaces thereof and being pressed against said rotating neck with sufficient pressure to cause the roll or rolls to be frictionally rotated thereby. This operation 20 frequently resulted in the formation of imperfect threads or in the distortion of the neck, or in both, the distortion of the neck being due to the pressure of the roll or rolls thereagainst.

25 The present invention aims to overcome these disadvantages of the rolling and pressing method by the provision of means for forming the threads by a cutting operation, such cutting operation involving an actual 30 removal of material from the tube neck as distinguished from the rolling and pressing operation which involves a displacement of the material of the tube neck.

In the accompanying drawings:

35 Figure 1 is a side elevation, partly broken away, of a machine embodying my invention,

Figure 2 is a plan view of the threading means and adjacent parts of the machine,

40 Figure 3 is a vertical sectional view on the line III—III of Figure 2,

Figure 4 is a vertical longitudinal sectional view of a portion of the cutter-carrying lever,

45 Figure 5 is a view, partly in side elevation and partly in vertical section, the section being taken on the line V—V of Figure 3, and

50 Figures 6 and 7 are a side elevation and edge view, respectively, of the cutter member.

While my invention is broadly applicable to various types of machines for manufac-

turing collapsible tubes, I have herein shown it as applied to a machine of the type illustrated in the patent to John A. McGinnis, No. 1,457,179 of May 29, 1923, which embodies means for cutting the formed tubes to length, means for forming screw-threads in the necks of the tubes, means for trimming the ends of said tubes, and means for applying caps to the threaded necks.

55 Referring to the drawings, the reference character A designates the frame of the machine. This machine is provided with a rotary mandrel-carrying turret 2 which is designed to have a step-by-step rotation, and which, carries four tube-holding rotatable mandrels 3. The actuating gears for the turret and mandrels are indicated by the 60 reference numeral 4, these gears being driven through a belt 5 from a power-shaft 6, the latter having fast and loose pulleys 7 thereon.

65 The machine may be provided with a feed hopper 8 of any well-known selective character and adapted to feed the caps into a suitable delivery chute 9 having an overflow spout 10. The chute 9 delivers the caps to a cap-applying device 11. The feed hopper is mounted for rotation and is provided for 70 that purpose with a bevel gear 12 meshing with a bevel gear 13 on a shaft 14, the latter being journaled in the bracket 15 which supports the hopper. The shaft 14 is driven from a shaft 16 through a belt 17 which engages pulleys 18 and 19 on the shafts 14 and 16, respectively, the shaft 16 being driven from the power-shaft 6 through a belt 20 engaging pulleys 21 and 22 on the said 75 shafts 6 and 16, respectively.

80 In the operation of the machine, the mandrel-carrying turret is given a step-by-step rotation to carry each mandrel successively into each of four operative positions 85 degrees apart. At one operative position into which each mandrel is brought, a collapsible tube to be operated upon is placed thereon by an operative; at the second position, the neck of each tube is threaded and the end thereof trimmed to open up the discharge 90 passage therein; at the third position, each tube is cut to length by a cutter 23, and a cap applied to the threaded neck thereof, and at the fourth position, each tube is removed 95 from its mandrel by the operative.

100 The thread-cutting means of the present

invention is illustrated in detail in Figures 2 to 7, inclusive, and comprises a cutter 24 secured by a screw-bolt 25 on the end of a lever 26. The cutter-carrying lever 26 is fixed intermediate its ends upon a shaft 27 journaled at its ends in bearings formed in brackets 28 and 29, which are bolted to the frame of the machine. Extending through the end of the lever 26 opposite to that on which the cutter 24 is secured, is an opening, the axis of which lies in a vertical plane, and adjustably secured in the opening by means of a set-screw 30 is a follower-pin 31 having its lower end double-beveled to a knife-edge to engage the threads of a lead-screw 32. This lead-screw is carried by a shaft 33 journaled in the frame A and driven from the shaft 16 through a pinion 34 on the shaft 33 meshing with a gear 35 on the shaft 16.

A coil-spring 36 surrounds the shaft 27 intermediate the lever 26 and the bracket 29, and has one end fastened to the lever and the other end fastened to the bracket, the tension of said spring being exerted to rotate said lever in a direction to move the edge of the follower-pin 31 out of engagement with the lead-screw 32 and to lower the cutter 24 out of operative position.

A flat spring 37 is fastened to the under surface of the arm of the lever 26 which carries the cutter 24, this spring being secured to the lever by a bolt 38 which passes through the lever and is screwed into a threaded opening in the spring adjacent the end thereof which is nearest the fulcrum of the lever. A screw 39 engages in a threaded bore in the lever 26 and abuts at its end against spring 37 intermediate the ends of the latter, whereby by adjusting the screw, the free end portion of the spring 37 may be sprung more or less away from the under face of the lever-arm for a purpose to be presently brought out. A lock-nut 40 on the screw 39 engages the upper face of the lever-arm and locks the screw in adjusted position.

The spring 37 has a downwardly directed shoulder 41 integrally formed on the free end thereof, which is engaged by the upper end of a pin 42 slidably mounted in a vertical bearing 43 formed in a housing B which surrounds the shaft 16. The lower end of the pin 42 is engaged by a cam member 44 carried by said shaft 16.

The shaft 16 also has mounted thereon a collar 45 having a cam groove 46 formed in the periphery thereof. This cam groove is engaged by the lower end of a pin 47, which is fixed to a carriage C slidably mounted upon the upper face of the housing B, said pin extending through a longitudinal slot 48 in said housing. The sliding carriage C has adjustably mounted thereon

a holder 49 for a neck-trimmer 50, the latter being moved into and out of operative position once during each revolution of the shaft 16, as will be obvious.

It will be apparent that during each revolution of the shaft 16, the cam 44 raises the pin 42, the latter, through its engagement with the spring 37, effecting a rocking of the lever 26 in a counter-clockwise direction, (Figure 3) and in opposition to the spring 36, thereby lowering the pin 31 to effect engagement of its beveled lower end with the lead-screw 32 and raising the cutter 24 into operative position with respect to the position occupied by the neck of a tube to be threaded. By adjusting the screw 39 to spring the free end portion of the spring 37 a greater or less distance away from the arm of the lever 26, the operative position of the cutter 24 may be very accurately adjusted.

The inoperative position of the lever 26 and the parts carried thereby is illustrated in Figure 1, and the operative position of these parts is illustrated in Figures 2, 3 and 5. It will be noted that in the inoperative position of the parts, the lever 26 is held by the spring 36 in engagement with the bracket 28. As soon as the cam 44 engages and raises the pin 42 to effect movement of the cutter 24 into operative position with respect to the neck of a tube D (Figures 2 and 5), the beveled edge of the pin 31 is brought into engagement with the rotating lead-screw 32. At this moment the cutter 24 is in engagement with the end of the neck surface of the tube D, and thereafter the lever 26, through the engagement of the pin 31 with the lead-screw 32, is gradually moved toward the bracket 29, thereby putting the spring 36 under compression, the shaft 27 sliding in its bearings in the brackets 28 and 29. The cam 44 is so shaped as to maintain the pin 42 in the raised position until the neck of the tube has been threaded from end-to-end, as indicated in Figure 5, and then to permit said pin to fall. As soon as this occurs, the spring 36 rocks the lever 26 in a clockwise direction (Figure 3), thereby effecting disengagement of the pin 31 from the lead-screw 32, and, immediately that this occurs, the said spring 36 moves the lever 26 into engagement with the bracket 28, which is the normal inoperative position of the lever and the parts carried thereby. It is obvious that by removing the cam 44 and substituting a differently shaped cam, the threading mechanism may be readily adapted to thread tubes having longer or shorter necks, or having necks of a greater or less diameter. Moreover, the adjustable spring 37 affords means for accurately adjusting the operative position of the cutter.

Referring to Figures 6 and 7, it will be

seen that the cutting point 51 of the cutter member 24 lies in an arcuate edge 52 formed by the intersection of bevel faces 53 and 54 on the periphery of the cutter member. The point 51 also lies in the substantially radial face 55 formed by cutting away the cutter member as shown. When the cutting point 51 becomes dull, the cutter member may be sharpened by grinding the face 55, thereby moving the cutting point 51 further back in the edge 52. It will be seen that the cutter is of such form that it may be repeatedly ground until the point 51 has been moved around substantially to the point 56 10 constituting the opposite end of the edge 52. Such form of cutter is, therefore, extremely economical because it admits of substantially the entire cutter member being used up before it has to be discarded. It will also be apparent that the mounting of the cutter 24 by means of the screw-bolt 25 admits of the cutter member being adjusted as the same is sharpened, from time to time, to properly position the cutting point 51 with respect to 15 the tube necks.

An important advantage arising from the invention is that, due to the provision of means for forming the threads in the necks of the tubes by a cutting operation, the necks 30 are relieved of the pressure tending to deform the same which is exerted by the roll or rolls in the forming and pressing operation, in which the friction between the tube neck and the roll or rolls must be sufficient 35 to cause the roll or rolls to be rotated by the rotating neck and to cause the threads on the roll or rolls to displace material of the neck in order to form the threads therein.

Another advantage arising from the invention is that it enables the formation of 40 more perfect threads in the necks of the tubes than heretofore.

A further advantage arising from the invention is that it provides a special form of 45 cutter member which may be repeatedly sharpened until the cutter member is substantially completely used up, thereby providing for economy of operation.

While I have shown and described a preferred embodiment of my invention, it will 50 be understood that the drawings do not define the limits of the invention, as changes may be made in the construction, arrangement and operation therein disclosed without departing from the spirit of my invention or scope of my broader claims.

I claim:

1. In a collapsible tube-working machine, tube-supporting and rotating means, a lever 60 fulcrumed intermediate its ends and mounted for bodily movement in the direction of its pivotal axis, a cutter mounted upon an arm of said lever and adapted to be moved thereby into and out of operative position 65 with respect to the neck of a tube on said supporting means, a lead-screw, follower means carried by the other arm of said lever and adapted to engage the threads of said lead-screw to cause a bodily movement of said lever in the direction of its pivotal axis, said lever normally maintaining said cutter in inoperative position and said follower means out of engagement with said lead-screw, and means for rocking said lever into a position in which said cutter is 70 in operative position and in which said follower means is in engagement with said lead-screw and for maintaining said lever in said position during a threading operation, substantially as described. 75

2. In a collapsible tube-working machine, tube-supporting and rotating means, a lever fixed intermediate its ends upon a shaft slideable and rotatable in spaced bearings, a cutter mounted upon one arm of said lever and adapted to be moved thereby into and out of operative position with respect to the neck of a tube on said supporting means, a lead-screw, follower means carried by the other arm of said lever and adapted to engage the threads of said lead-screw to cause a bodily movement of said lever in the direction of its pivotal axis, a coil spring surrounding said shaft between said lever and one of said bearings and tending to rock said shaft in a direction to maintain said cutter in inoperative position and said follower means out of engagement with said lead-screw and to move said lever towards the other of said bearings, and means for rocking said lever into a position in which said cutter is in operative position and in which said follower means is in engagement with said lead-screw and for maintaining said lever in said position during a threading operation, substantially as described. 90

3. In a collapsible tube-working machine, tube-supporting and rotating means, a lever fulcrumed intermediate its ends and mounted for bodily movement in the direction of its pivotal axis, a cutter mounted upon an arm of said lever and adapted to be moved thereby into and out of operative position with respect to the neck of a tube on said supporting means, a lead-screw, follower means carried by the other arm of said lever and adapted to engage the threads of said lead-screw to cause a bodily movement of said lever in the direction of its pivotal axis, said lever normally maintaining said cutter in inoperative position and said follower means out of engagement with said lead-screw, a flat spring fastened to the cutter supporting arm of said lever, adjustable means for springing said spring away from 110 said arm, and cam means engageable with said spring for rocking said lever into a position in which said cutter is in operative position and in which said follower means is 115 in engagement with said lead-screw and for 120

maintaining said lever in said position during a threading operation, substantially as described.

4. In a collapsible tube working machine, a tube supporting and rotating means, a slidably supported lever movable longitudinally of the tube supporting and rotating means, a cutter on the lever, a continuously rotated means for sliding the lever, means for periodically rocking the lever to bring the cutter into operative position, and means on the lever for cooperation with the continuously rotated means only when the lever is moved to bring the cutter into operative position.
5. In a collapsible tube working machine, a bed, tube supporting and rotating means

over the bed, a longitudinally extending shaft under the bed, a second shaft parallel with the first located at the side of the bed of machine, means for rotating both shafts, 20 a cutter supporting member with a cutter thereon, a cam on the first shaft having means cooperating therewith for moving the cutter supporting means vertically into and out of operative position, and means on the second shaft cooperating with means on the cutter supporting member for transmitting longitudinally reciprocable movement thereto.

In testimony whereof I have hereunto set 30 my hand.

WALTER T. DAVIS.
